No. 839,688.

PATENTED DEC. 25, 1906.

J. H. WILLIAMS.
FRESH AIR CABINET.
APPLICATION FILED MAR. 15, 1906.

UNITED STATES PATENT OFFICE.

JOSIAH HARRY WILLIAMS, OF COLUMBIA, SOUTH CAROLINA.

FRESH-AIR CABINET.

No. 839,638.

Specification of Letters Patent.

Patented Dec. 25, 1906.

Application filed March 15, 1906, Serial No. 306,172.

To all whom it may concern:

Be it known that I, JOSIAH HARRY WILLIAMS, a citizen of the United States, and a resident of Columbia, in the county of Richland and State of South Carolina, have invented a new and Improved Fresh-Air Cabinet, of which the following is a full, clear, and exact description.

This invention relates to what is generally known as a "fresh-air" cabinet or device for application to a window forming an inclosure which is open to the outer air and in which the head of a person may be rested while the rest of the body is covered in bed in the usual manner. By these means the person is enabled while sleeping to breathe in the open air without subjecting the body to exposure to the weather.

The leading object of my invention is to provide a cabinet with means enabling it to be snugly folded when not in use; and to this end I construct the cabinet with an extensible frame, which may fit into the open window and to which is attached an extensible hood, suitably braced and provided at its outer end with a frame carrying a curtain arranged to fit snugly around the throat of the user, so that the head of the person may be rested within the cabinet, which communicates freely with the outer air, while drafts are not permitted to pass the curtain, thus protecting the body of the person from exposure. The first-named or main frame is also provided with a curtain, which may be adjusted at will to regulate the opening from the interior of the cabinet into the atmosphere.

Various other features of major or minor importance are involved, and all will be fully set forth hereinafter, and particularly pointed out in the claims.

Reference is to be had to the accompanying drawings, which illustrate as an example the preferred embodiment of my invention, in which—

Figure 1 is a sectional view showing the invention in use. Fig. 2 is an outer elevational view of the main frame; and Fig. 3 is an inner elevational view of the secondary or auxiliary frame, showing also the curtain thereof.

The main frame comprises a rigid rectangular section 10 and two adjustably-fitted sections 11, which lie against the outer side of the main section 10 and have projecting arms 12, adapted to be fastened to the main

section by means of clips 14. In this manner the adjustable sections 11 may be moved toward or from each other for the purpose of securely engaging the main frame in the window-frame below the sash, as shown in Fig. 1. The main frame has felt gaskets or the like 15 at its upper and lower edges, which engage the bottom of the window-frame and the lower edge of the sash, while the adjustable sections 11 are movable out, so that they fit snugly against the sides of the window-frame, thus securely engaging the main frame with the frame of the window. If desired, the top and bottom rails of the section 10 may be joined to the arms 12 by means of a tongue and groove, as shown in the sectional part of Fig. 1. Attached to the rigid section 10 of the main frame is an extensible hood 16, which is formed with accorded plait, so that it may be folded snugly flat against the main frame or extended, as shown in Fig. 1. The hood is held extended by means of jointed brace-rods 17, which are pivoted to the main frame and to the auxiliary frame 18, to which auxiliary frame the outer end of the hood 16 is fastened. These brace-rods 17 hold the auxiliary frame 18 extended, as shown, and they also may be caused to collapse, thus allowing the hood to be folded flat, as explained.

Hinged to the lower part of the auxiliary frame 18 is a pillow-support 19, which is sustained at its free portion by means of stay-links 20, each of which is formed of two jointed sections pivotally connected to the auxiliary frame and adjustably connected to the pillow-support. The auxiliary frame is provided with a curtain 21, which is wound over a roller 22 at the upper part of the frame and is provided with the usual catches 23 for holding the curtain in the desired position. These catches may be of any desired form—for instance, those commonly employed in car-window curtains—the catches 23 engaging in vertical grooves extending along the inner sides of the side rails of the auxiliary frame 18. The curtain 21 is provided at its lower portion with an opening 24 to receive the neck of the user, and surrounding this opening the curtain is braced by a wire or rod 25, which is secured in the curtain, as indicated by the broken lines in Fig. 3. The wires or rods 25 form a clasp which extends around the neck of the user and, as shown in broken lines in Fig. 3, the upper part of the clasp is so arranged that when the spring-

catches are pressed to release the curtain, so that the latter can be moved up or down, the clasp is also widened, so that it is easily removed from around the neck. The main frame is provided with a curtain 26, which serves to regulate the amount of air moving through the main frame. This curtain is wound at its upper edge around a roller 27, and at its lower edge it is provided with a suitable catch 28, similar to the catch 23, before described, working against the inner side edges of the main frame.

In the use of the invention the main frame is adjustable in the open window, as explained, and the hood 16 is extended and held by the adjustable brace-rod 17. Preferably the auxiliary frame 18 is rested on a bed or couch, and the pillow-support 19 is then thrown down and adjusted by the stays 20 to hold the pillow and permit the patient to lie thereon, as shown in Fig. 1. The curtain 21 should then be drawn down and fastened by the catches 23 or by any other suitable means, so that it snugly surrounds the throat of the user, as shown in Fig. 1. The opening of the cabinet into the outer air may be controlled readily by adjustment of the curtain 26, and by raising the curtain slightly from the position shown in Fig. 1 air may be allowed to circulate into the lower part of the cabinet and out above the curtain, thus at all times supplying the user with absolutely pure air. The device also prevents the exposure of other inmates in the room to the diseased germs of the user. When the device is not in use, it may be folded either against the window or it may be entirely removed from the window and stowed away in any other convenient place.

Having thus described the preferred form of my invention, what I actually claim, and desire to secure by Letters Patent, is—

1. A fresh-air cabinet comprising a main frame, a collapsible hood attached thereto, an auxiliary frame attached to the outer part of the hood, and a jointed brace extending between the two frames.

2. A fresh-air cabinet having a main frame, a collapsible hood attached at one end thereto, an auxiliary frame to which the other end of the hood is attached, a curtain attached to the main frame, and means connected with the frames for holding the hood extended.

3. A fresh-air cabinet comprising a main frame, a collapsible hood attached thereto, an auxiliary frame attached to the outer part of the hood, a jointed brace extending between the two frames, and a curtain attached to each frame, the curtain of the auxiliary frame having an opening therein to receive the neck of the user.

4. A fresh-air cabinet comprising a main frame, a collapsible hood attached thereto, an auxiliary frame attached to the outer part of the hood, a jointed brace extending be-

tween the two frames, a pillow-support hinged to the auxiliary frame within the hood, and means for holding the pillow-support in active position.

5. A fresh-air cabinet comprising a main frame, a collapsible hood attached thereto, an auxiliary frame attached to the outer part of the hood, means connecting the two frames to hold the hood extended, a pillow-support hinged to the auxiliary frame within the hood, and means for removably holding the pillow-support in active position.

6. A fresh-air cabinet comprising a main frame, a collapsible hood attached thereto, an auxiliary frame attached to the outer part of the hood, means connecting the two frames to hold the hood extended, a pillow-support hinged to the auxiliary frame within the hood, means for removably holding the pillow-support in active position, and a curtain attached to each frame.

7. A fresh-air cabinet, comprising a main rectangular frame having an adjustable portion fitted into a window-frame, an extensible hood attached at one end to the main frame, an auxiliary frame to which the other end of the hood is attached, and a curtain attached to each frame.

8. In a fresh-air cabinet, a main frame having an adjustable portion adapted to fit in a window-frame, a hood attached at one end to said frame, and a curtain supported at the other end of the hood and arranged to fit around the throat of the user.

9. In a fresh-air cabinet, a rectangular frame, a curtain attached thereto, a hood attached at one end to the frame, a curtain supported at the other end of the hood, and a pillow-support within the hood.

10. A fresh-air cabinet, comprising a main frame, an auxiliary frame, an accordion-plaited hood attached at its ends to the frames and adapted to be extended or folded as desired, means for holding the hood extended, and a curtain attached to each frame.

11. A fresh-air cabinet, comprising a main frame, an accordion-plaited hood attached at one end to the main frame, an auxiliary frame to which the other end of the hood is attached, means for holding the hood extended, a curtain attached to each frame, a pillow-support hinged to the lower end of the auxiliary frame, and extending into the hood, and jointed stay-links pivotally connected to the auxiliary frame and adjustably connected to the pillow-support to hold the latter in position.

12. A fresh-air cabinet comprising a main frame provided with gaskets at its upper and lower edges for engaging the lower edge of a sash and the bottom of a window-frame, the said main frame having adjustable sections for engaging the sides of the window-frame, an extensible hood attached at one end to the main frame, an auxiliary frame to which the

5 other end of the hood is attached, a curtain carried by the auxiliary frame and provided at its lower portion with an opening to receive the neck of the user, catches for holding the curtain in position, and means for bracing the curtain around the said opening.

10 13. A fresh-air cabinet, comprising a main frame adapted to fit into an open window and provided with adjustable sections for engaging the sides of the window-frame, a hood attached at one end to the main frame, an auxiliary frame to which the other end of the

hood is attached, a curtain carried by the auxiliary frame and provided at its lower end with an opening to receive the neck of the user, and means for bracing the curtain around the opening. 15

In testimony whereof I have signed my name to this specification in the presence of two subscribing witnesses.
